UNITED STATES PATENT OFFICE

148,603

DESIGN FOR A BOOK END

Otto Edwin Berg, Washington, D. C.

Application October 17, 1946, Serial No. 134,007

Term of patent 14 years

(Cl. D33—1)

To all whom it may concern:

Be it known that I, Otto Edwin Berg, a citizen of the United States, residing at the city of Washington, in the District of Columbia, have invented a new, original, and ornamental Design for Book Ends, of which the following is a specification, reference being had to the accompanying drawing, forming part thereof.

In the drawing:

Figure 1 is a perspective view of the new ornamental book end;

Figure 2 is a top plan view of the book end as shown in Figure 1;

Figure 3 is a front view in elevation of said book end; and

Figure 4 is a side view in elevation of said book end.

The dotted lines indicate an area at which is disposed a selected picture, symbol, insignia or emblem.

I claim:

The ornamental design for a book end, as shown and described.

OTTO EDWIN BERG.
